UNITED STATES PATENT OFFICE

154,829

DESIGN FOR AN AIRPLANE

Daniel R. Zuck, Los Angeles, Calif.

Application April 22, 1946, Serial No. 128,831

Term of patent 14 years

(Cl. D71—1)

To all whom it may concern:

Be it known that I, Daniel R. Zuck, a citizen of the United States, residing at Los Angeles, in the county of Los Angeles and State of California, have invented a new, original, and ornamental Design for an Airplane, of which the following is a specification, reference being had to the accompanying drawing, forming part thereof.

Fig. 1 is a perspective view of the airplane embodying my new design and illustrating the same as it appears in flight position; Fig. 2 is a view in front elevation of the airplane; Fig. 3 is a top plan view of the same; Fig. 4 is a view in side elevation of the same; Fig. 5 is a perspective view of the same but illustrating the wings in collapsed position; Fig. 6 is a view in side elevation of the plane in collapsed position; Fig. 7

is a top plan view of the airplane in collapsed position; and Fig. 8 is a view in front elevation of the same in collapsed position.

I claim:

The ornamental design for an airplane, as shown.

DANIEL R. ZUCK.
